UNITED STATES PATENT OFFICE

HUGO WIENER, OF BISBEE, ARIZONA

ELECTRIC PICK-UP FOR PHONOGRAHS

Application filed April 18, 1930. Serial No. 445,399.

My invention relates to improvements in electric pick ups for phonographs, and it consists in the combinations, constructions, and arrangements herein described and claimed.

5 An object of my invention is to provide an electric pick up for phonographs in which novel means is provided whereby sound waves as represented on a phonograph record may be converted into exactly similar electrical impulses, thereby providing an efficient converting mechanism.

10 A further object is to provide a device of the type described embodying means for reproducing the audio frequencies with uniformity and free from distortion.

15 A further object is to provide a device of the type described in which a novel electromagnet is provided and having its pole pieces characterized by a circular opening, and in which a movable coil is disposed in operative 20 relation with the electromagnet and within said opening whereby a peculiarly sensitive construction is attained.

25 Other objects and advantages will appear in the following specification, and the novel features of the invention will be particularly pointed out in the appended claim.

30 My invention is illustrated in the accompanying drawing, forming part of this application, in which

Figure 1 is an elevation of a tone arm embodying my invention,

Figure 2 is a sectional view taken along the line 2-2 of Figure 1, and

35 Figure 3 is a sectional view taken substantially along the line 3-3 of Figure 2.

40 In carrying out my invention I make use of a tone arm 1 provided with a head 2 which, in referring to Figure 2, it will be noted comprises a casing 3 having a relatively large opening 4 and a central opening 5 in one of its sides. The casing is provided with a pin 6 which is concentrically positioned with respect to the opening 5. In Figure 2 I have shown a field coil 7 as being mounted upon the pin 6. The coil may be energized by any suitable source of current through conductors 8.

45 In Figures 1 and 2 I have shown rubber lugs 9 as being secured to the face of the

casing 3 having the opening 5 therethrough. The lugs 9 movably support a shaft 10 which in turn carries a staff 11 provided with a needle 12. The shaft 10 is mounted for rotation about its longitudinal axis which, of course, permits a similar action of the staff 11.

55 A movable coil 13 is mounted upon the upper end of the staff 11. The coil comprises a tubular member 14 which is made from suitable insulating material and is provided with spokes 15, whereby the tubular member may be secured to the staff through the medium of a pin or rivet 16. The tubular member is provided with the required number of turns of suitable wire as indicated at 17. 60 The movable coil may be operatively connected with an amplifier through the medium of leads 18.

65 It will be noted in referring to Figure 2 that the movable coil is concentrically positioned with respect to the opening 5 and the pin 6. The coil is accurately centered and supported in its proper aligned position by means of a centering device comprising strap members 19 having their outer ends secured to the face of the casing 3 by means of rivets or screws 20. The inner ends of the strap members are connected together and secured to the staff through the medium of the rivet 16. The centering device is formed 70 from a suitable material which will permit the movable coil to move in parallelism with the longitudinal axis of the pin 6, but which at all times prevents lateral movement of the coil.

75 In operation, the head 2 in connection with the coil 7 provides an electromagnet having its pole pieces defined by the opening 5. A magnetic field of great density is built up in the opening 5 by reason of the field coil. 80 The relatively low number of turns of the wire in the movable coil 13 provides a low inertia and reactance of the movable coil. The undulations on the record cause a relative movement of the staff 11 which in turn is conveyed to the movable coil 13. Due to the fact that the vibrating coil is positioned within a dense magnetic field, the coil will, 85 of course, induce a corresponding potential in the winding of the coil. This alternating 90

potential in being properly amplified by suitable mechanism, not shown, will provide a perfect reproduction through a loud speaker.

I claim:—

- 5 A device of the character described comprising a hollow electromagnet having an annular airgap therein and a stationary magnetic pin centrally disposed in said airgap, a moving coil member disposed in said airgap and surrounding said pin, two rubber lugs attached to said magnet and having aligned openings therein, a circular rod having one end loosely mounted in each of said openings, a needle supporting strap-supported shaft operatively connected to said coil member mounted loosely on said rod at a substantially central portion of said shaft and said rod, said movable coil member comprising a tubular insulating body disposed in said airgap, and a helical coil rigidly attached to the cylindrical insulating member, said rubber lugs resiliently and loosely supporting said rod.
